CLAIM

The ornamental design for a pipe lifting elevator ear, as shown and described.

DESCRIPTION

FIG. 1 is a top front perspective view of a pipe lifting elevator ear showing my new design;

FIG. 2 is a top rear perspective view thereof;

FIG. 3 is a bottom front perspective view thereof;

FIG. 4 is a bottom rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top plan view thereof;

FIG. 10 is a bottom plan view thereof;

FIG. 11 is a sectional view thereof taken along line 11-11 of FIG. 8;

FIG. 12 is a sectional view thereof taken along line 12-12 of FIG. 8;

FIG. 13 is a sectional view thereof taken along line 13-13 of FIG. 8;

FIG. 14 is a sectional view thereof taken along line 14-14 of FIG. 8;

FIG. 15 is a sectional view thereof taken along line 15-15 of FIG. 8; and,

FIG. 16 is a sectional view thereof taken along line 16-16 of FIG. 8.

The broken lines depict portions of the article that form no part of the claimed design.
